UNITED STATES PATENT OFFICE.

KARL STEINBECKER, OF CHARLOTTENBURG, GERMANY, ASSIGNOR TO GENERAL ELECTRIC COMPANY, A CORPORATION OF NEW YORK.

PISTON-COOLING DEVICE FOR INTERNAL-COMBUSTION ENGINES.

1,063,615.

Specification of Letters Patent.

Patented June 3, 1913.

Application filed September 7, 1911. Serial No. 642,012.

To all whom it may concern:

Be it known that I, KARL STEINBECKER, a subject of the King of Prussia, residing at Charlottenburg, Germany, have invented 5 certain new and useful Improvements in Piston-Cooling Devices for Internal-Combustion Engines, of which the following is a specification.

This invention relates to internal combustion engines, and especially to those in which the piston is provided with a chamber for a cooling medium, conveyed into and out of said chamber by means of telescopic pipes. One section of each of said pipes is stationary, while the other is secured to the piston and moves therewith. Heretofore a stuffing-box has been used to make a fluid-tight joint between said fixed and movable pipe sections, but this consumes power and 20 is quickly worn out when the engine runs rapidly. By my invention the stuffing-boxes are dispensed with, and an improved arrangement of pipes is provided in which a narrow annular gap of considerable length 25 is left between the relatively movable sections which effectually packs the joint.

The accompanying drawing is a longitudinal section of the piston of an internal combustion engine equipped with my invention.

I have shown only a portion of the engine cylinder 1, containing the packed piston 2, which has the usual cross-pin 3 for the attachment of the pitman. The piston is hollow, having a chamber 4 for a cooling medium, such as water, which is caused to circulate through said chamber to carry off any excess of heat. The chamber communicates with two tubes 5, 6 secured to the 40 piston with their axes parallel with that of the cylinder 1. These tubes coöperate, respectively with stationary pipes or tubes 7, 8, over which they slide telescopically or trombone fashion. The cooling fluid is conveyed to the chamber 4, through the pipe 7 and tube 5, and finds exit from said chamber through the tube 6 and pipe 8. The pipes lie close to the tubes, but do not touch them, so that there is left an annular gap 9, 45 narrow enough and long enough to throttle most of the cooling fluid which attempts to escape between said pipes and tubes. A small quantity of said fluid will, however, find its way through the throttling gap, and 50 in order to collect and drain off this leakage

fluid I provide a tubular jacket 10 for each telescopic pipe. Each jacket is stationary, its upper end containing a throttling section 11 coöoperating with the movable tubes 5, 6 and affording a narrow gap of sufficient 60 length to pack the joint. The lower part 12 of the jacket is preferably of greater capacity than the upper portion to permit a considerable accumulation of leakage fluid in case it flows for a short time faster than 65 the drainage outlet or pipe 13 can carry it away from said jacket. The cooling water is brought to the admission pipe 7 by the pipe 14 and is led off from the exit pipe 8 by the pipe 15. The pipes 7 and 8 may be conveniently supported by a plug 16 inserted into the lower end of the jacket 10, which in turn is supported preferably by an arm 17 attached to the cylinder 1. The leakage of the cooling fluid through the long narrow throttling gap will be smaller in proportion to the length and cross-section of said gap. The throttling section 11 may be dispensed with if the jacket is high enough and large enough and the drain pipe big enough to prevent the 70 leakage fluid from overflowing the top of the jacket.

The invention is applicable to horizontal as well as to upright engines.

In accordance with the provisions of the 85 patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is— 95

1. The combination with a cylinder and a hollow piston therein, of means for conveying cooling fluid to and from the piston, comprising two stationary concentric pipes or tubes, and a third tube secured to the piston and extending into the annular space between the first two tubes, the relatively movable sections of said tubes being packed by means of the throttling gap between them. 100
2. The combination with a cylinder, of a hollow piston, stationary pipes parallel with the axis of said cylinder, tubes secured to said piston and telescoping over said stationary pipes, said pipes and tubes being of such length and diameter as to provide a 105
110

relatively long, narrow throttling gap between them, and cylindrical jackets surrounding the tubes and separated from the outer walls thereof by a narrow annular space.

3. The combination with a hollow piston, of telescopic pipes connected therewith and affording throttling gaps between them, and stationary jackets surrounding said pipes and provided with drainage outlets.

4. The combination with a hollow piston, of telescopic pipes connected therewith and affording throttling gaps between them, and jackets surrounding said pipes and provided with drainage outlets at their lower ends and with throttling gap packing at their upper ends.

5. The combination with a cylinder and a hollow piston therein, of means for conveying cooling fluid to and from the interior of the piston, comprising two concentric pipes or tubes mounted on the cylinder, a fluid conveying conduit connected to the inner tube, a drain for conveying leakage from the outer tube, and a third tube connected to the interior of the piston and extending into the annular space between the first two tubes, there being a relatively

small clearance between it and the walls of the other tubes.

6. The combination with a cylinder and an open ended piston therein having a water chamber at its closed end, of means for conveying cooling fluid to and from the chamber, comprising a tubular member secured to the cylinder and projecting into the open end of the piston, the outer portion of said member being of larger internal diameter than its inner portion, a drain leading from the enlarged portion of said member, a concentrically arranged tube within said member, one end of the tube being secured in the outer end of the member, a fluid conveying conduit connected to the tube, and a third tube connected to the chamber in the piston and extending into the annular space between the first two tubes, there being a relatively small clearance between it and the walls of the other tubes.

In witness whereof, I have hereunto set my hand.

KARL STEINBECKER.
